COMBINATION CARBURETOR AND
IGNITION SYSTEM

Marion Mallory, Detroit, Mich.

Original application March 2, 1942, Serial No.
432,947. Divided and this application June 1,
1942, Serial No. 445,317

4 Claims. (Cl. 123—117)

This invention relates to a combination carburetor and ignition system.

In most present-day carburetors the fuel jet is positioned between the throttle valve and atmosphere. The vaporizing of the fuel as it flows from the fuel nozzle creates refrigeration which frequently causes the throttle to freeze, and in particular where the carburetor is used in an airplane flying at high altitude.

One of the features of this invention is that of producing a carburetor wherein the fuel nozzle is positioned between the throttle and the engine so that the atomized fuel mixtures do not freeze on the throttle or in the carburetor body because the atomization takes place in or adjacent to the hot spot located in the intake manifold on the engine side of the throttle valve.

Another feature of this invention is that condensation of the atomized fuel is prevented. Since the fuel nozzle is positioned on the outlet side of the throttle valve the atomized fuel cannot strike the cold throttle valve or cold walls of the carburetor which would cause condensation of the fuel.

Another object of the invention is that of pre-mixing or atomizing a metered amount of fuel with a metered amount of air before the atomized mixture passes out of the fuel nozzle into the venturi or mixing chamber of the carburetor where it is mixed with additional amounts of air flowing through the main passageway of the carburetor.

This invention also contemplates a carburetor and ignition system in which the ignition timing is controlled entirely by the charge flowing through the carburetor venturi at wide open throttle, that is, under full load conditions, and controlled principally by the vacuum existing in the manifold on the engine side of the throttle valve when the carburetor is operating under all conditions except wide open throttle or at idle position of the throttle.

The figure is a vertical cross sectional view through the carburetor and ignition system.

Referring more particularly to the drawing, 45 the carburetor housing is designated 30 and is provided with an air inlet 31 and a fuel and air outlet 32 on the engine side of the throttle valve 2 mounted on valve shaft 13. Valve shaft 13 is journaled in the housing 30 in a conventional manner. Valve 2 is an unbalanced throttle valve, that is, the area of the throttle valve 2 on one side of the shaft 13, or to the right of shaft 13, is greater than the area of the portion of the throttle valve on the other side, or to the left 50

of shaft 13. Thus, if unbalanced valve 2 is unrestricted, the vacuum in the manifold will open the valve due to its unbalanced nature.

The manually controlled throttle rod 12 is pivotally connected to throttle arm or plate 33 which is journaled on shaft 13 with a lost motion connection and exterior of the housing 30. An arm 34 is fixed on the same end of shaft 13 as plate 33, also exterior of the housing 30. Plate 33 is provided with the spaced lugs 35 and 36 which engage opposite sides of arm 34 when plate 33 is turned on shaft 13. The lugs 35 and 36 are spaced so that there is a lost motion between shaft 13 and plate 33 when the plate is rotated by rod 12. In other words, if plate 33 is held still, arm 34 is free to rotate between lugs 35 and 36. This lost motion, as shown by way of description rather than for purposes of limitation, amounts to about 20°.

A link 5 is pivotally connected at one end with plate 33 and at the other end with metering pin 4 which slides up and down in passageway 37 and controls orifice 6. Orifice 6 connects into passageway 11. The upper end of passageway 11 communicates with atmosphere through orifice 10 and the lower end of passageway 11 communicates with the interior of the float bowl 38 of the carburetor through orifice 7. Passageway 37 communicates through passageway 8 and fuel orifice 39 with the venturi 9 of the main carburetor passageway.

The arm 34 is connected by rod 40 with diaphragm 41 of a suction device 15 backed up by a compression spring 16 which tends to hold the throttle valve 2 in idle position as shown. The suction device 15 communicates by means of conduit 42 with quill 14 positioned in the intake passageway on the atmosphere side of the throttle valve. The left hand side of the diaphragm 41 is open to atmosphere whereas the right hand side of the diaphragm 41 and the interior of the right hand portion of the suction device 15 communicates with atmosphere only through conduit 42, quill 14 and the intake passageway of the carburetor.

The operation of the carburetor as thus far described is as follows: Assume that throttle valve 2 is practically closed, that is, just open enough to permit a sufficient charge of air to flow by the throttle for idling of the engine, at this time the metering pin 4 is almost closed but permits enough fuel to flow through orifice 6 for the engine to idle. This fuel passes from the float bowl into channel 7, through orifice 6, passageways 37 and 8, and through nozzle 39 into the venturi 9. Simultaneously with the flow of fuel

through orifice 6, air passes through orifice 10 into passageway 11 and into orifice 6 where it intermixes with the fuel and flows with the fuel through passageways 37 and 8 and orifice 39 into venturi 9, where this rich mixture of fuel and air is further intermixed with the main air charge flowing through the main passageway of the carburetor and venturi 9. As the throttle 2 is moved towards open position from idle more air and more fuel are admitted through orifice 6 because the metering pin with its tapered face 43 is raised. Thus, the air and fuel passing through orifice 6 are metered simultaneously and through the same orifice.

If the throttle rod 12 is pulled toward the left in Fig. 1 to open the throttle 2, the rod 12 and arm 33, due to the lost motion connection with arm 34, will move a considerable distance before the manifold suction begins to open the throttle valve and as the throttle rod is pulled or moved outwardly or to the left, the metering pin 4 will move a considerable distance upwardly before the throttle valve starts to open. This makes the fuel mixture a little richer for sudden acceleration. As the engine speeds up following the partial opening of the unbalanced throttle valve 2 by the suction, the air velocity past quill 14 causes the diaphragm in suction device 15 to open valve 2 against the force of compression spring 16 within the limits permitted by stop lugs 35 and 36 on arm 33. Of course, if the throttle rod 12 is pulled wide open or to the left, then clockwise rotation of arm 33 causes lug 36 to engage the left hand edge of arm 34 to rotate the same clockwise and open the throttle valve wide in spite of spring 16 which is compressed by this manual opening of the throttle valve 2.

The timing mechanism is conventional and as shown consists of the usual rotatable cam 46 which operates the electrical circuit breaker 47. The circuit breaker 47 is mounted on the plate 48 which can be rotated clockwise to advance the spark and counterclockwise to retard the spark. A suction device 20 is used for advancing and retarding the spark. This suction device comprises a flexible diaphragm 49 backed up by a compression coil spring 50. The diaphragm 49 is mounted in the housing 51 which is connected to the carburetor by conduit 52. The diaphragm is connected to plate 48 by connecting rod 53, one end of which is pivotally connected to the plate 48 and the other end of which is fixed to the diaphragm. The left hand wall of the housing 51 is perforated so that the diaphragm is subjected on the outside, or left hand side as viewed in the drawing, to atmospheric pressure whereas the inside of the housing 51, that is, the right hand side of the diaphragm 49, is subjected through conduit 52, orifice 19 and passageway 17 and orifice 23 to the vacuum created by the flow or velocity of the air through venturi 9 and by orifice 23. Communication between orifice 19 and passageway 17 is controlled by valve 18 and compression spring 21 which normally tends to elevate valve 18 thereby permitting communication between orifice 19 and passageway 17. Passageway 55 communicates at one end with orifice 22 positioned in the intake passageway on the atmosphere side of throttle valve 2 and the other end of passageway 55 continuously communicates with conduit 52.

The ignition timing operates as follows: The vacuum on the engine side of valve 2 is always highest when the valve is closed for idling and the engine is idling. At this time the manifold

suction acts through passageway 17 to draw piston valve 18 downwardly against spring 21 and thereby shut off orifice 19. In other words, when valve 18 closes orifice 19, suction device 20 is shut off from communication with the engine manifold suction. As the throttle 2 is moved towards an open position, as above described, the suction in the manifold will decrease and spring 21 will move piston 18 upwardly to clear or open orifice 19 thereby placing the suction device in communication with the intake passageway below throttle valve 2 and thereby subjecting the suction device to the intake manifold vacuum which advances the spark for light load or part throttle operation. The orifice 22 bleeds the manifold suction down under part load or part open throttle conditions, particularly at slow engine speeds, so that the spark is not advanced far enough to cause detonation or pre-ignition. This bleeding down of the manifold vacuum permits one to use the same suction device for controlling the ignition by use of the manifold suction as well as the suction created by the velocity of air flowing through the venturi. The venturi created suction is less powerful than the manifold suction at idle or part throttle. By bleeding the suction down at part load or part open throttle when the manifold suction is high, one can use the same suction device not only under part open throttle conditions but also under wide open throttle conditions when the venturi created suction is less powerful and yet obtain the required advance of the spark as the speed of the engine or velocity of air through the venturi increases. When the throttle 2 is wide open the ignition is timed by the vacuum or suction created by the flow of air by orifice 23 in venturi 9 so that as the speed of the engine increases under wide open throttle 40 the vacuum at orifice 23, which is applied through passageways 17 and 52 on diaphragm 49, advances the spark correspondingly.

The outlet end 32 of the carburetor connects on to the intake manifold of the internal combustion engine with which the carburetor is used.

This application is a division of application Serial No. 432,947, filed March 2, 1942.

I claim:

1. In combination, a carburetor for an internal combustion engine, the said carburetor having a passageway provided with an inlet and an outlet, a throttle valve in said passageway, the said inlet being positioned on the atmosphere side and the said outlet being positioned on the manifold side of said throttle valve, a venturi in said passageway on the outlet side of the throttle valve, a conduit having one end terminating in the venturi and the other end terminating in the carburetor passageway on the atmosphere side of the throttle valve, and a suction controlled ignition timing device connected into said conduit between the ends of the conduit whereby when the throttle valve is partly open the timing is principally controlled by the vacuum on the manifold side of the throttle valve air bled by the portion of the conduit communicating with atmosphere and at wide open throttle the timing is controlled principally by the vacuum created by the flow of air through the venturi past the end of the conduit.

2. The combination as claimed in claim 1 having a valve positioned in the conduit responsive to the vacuum on the outlet side of the throttle valve when in idle position to shut off the suction device from the venturi whereby at idle posi-

tion the suction device is subjected substantially to atmospheric pressure and the spark is retarded.

3. In an internal combustion engine the combination of an ignition timer and a carburetor having a passageway including a venturi, a throttle valve on the atmosphere side of the venturi, a conduit having an outlet in the venturi and another outlet into the carburetor passageway on the atmosphere side of the throttle valve, a suction device communicating with the above-mentioned conduit coordinated with the relatively low vacuum set up in said conduit by said venturi when the throttle is in approximately full load or wide open position whereby the suction device is operable to control said ignition timer

5 by the said relatively low vacuum in accordance with the speed of the air flowing through the venturi at wide open throttle and whereby when the throttle valve is partly open the suction device is subjected primarily to the engine intake manifold vacuum reduced by air bleeding into the conduit from the atmosphere side of the throttle valve.

10 4. The combination as claimed in claim 3 including a valve in the said conduit responsive to the vacuum on the outlet side of the throttle valve in idle position to close off the venturi from the suction device and thereby retard the spark at idle.
